COMBINED POCKET KNIFE AND BOTTLE OPENER

Felix V. Amoroso, 1144 Narragansett Blvd.,
Cranston, R.I.

Filed July 19, 1960, Ser. No. 61,425

Term of patent 14 years

(Cl. D22—3)

FIG. 1

FIG. 2

FIG. 3

FIG. 4

FIG. 5

FIG. 1 is a side elevational view of a combined pocket knife and bottle opener showing my new design.

FIG. 2 is a top plan view thereof.

FIG. 3 is an end view thereof as seen from the right of FIG. 1.

FIG. 4 is a bottom plan view thereof.

FIG. 5 is a perspective view with the bottle opener and the knife blade in partly open position.

I claim:

The ornamental design for a combined pocket knife and bottle opener, as shown.
